UNITED STATES PATENT OFFICE.

JACQUES HOHL, OF WEST HOBOKEN, NEW JERSEY.

LOOM.

SPECIFICATION forming part of Letters Patent No. 678,106, dated July 9, 1901.

Application filed July 8, 1900. Serial No. 22,420. (No model.)

To all whom it may concern:

Be it known that I, JACQUES HOHL, a citizen of the United States, residing at No. 619 Savoye street, West Hoboken, in the county of 5 Hudson, State of New Jersey, have invented certain new and useful Improvements in Looms, of which the following is a specification.

This invention relates to what are known 10 as "needle-looms;" and it consists in certain new organizations of devices, hereinafter set out in detail, whereby the operation of the loom is improved and rendered more certain, exact, and uniform.

15 The improvements are applicable to looms of various types for weaving various materials.

In the accompanying drawings, Figure 1 is 20 a plan view of so much of the machine as is requisite to the purpose of illustrating the invention; Fig. 2, an end elevation thereof; Fig. 3, a front elevation, partly in section, on the line 3 3 of Figs. 1 and 2. Fig. 4 is a 25 detail perspective view showing the devices for taking the looped weft-thread from the needle and the shuttle carrying the selvage-thread and the coacting parts; Fig. 5, a side elevation of the parts shown in Fig. 4, but in a different position. Figs. 6, 7, and 8 are plan 30 views respectively illustrating the operation of taking the weft-loop from the needle, passing the loop over the shuttle, and finally delivering the loop to be drawn down against the selvage-thread. Fig. 9 is a detail enlarged 35 plan showing the tension device carried by the needle.

Except as herein specified the loom may be of ordinary construction, and in the drawings it has not been considered necessary to 40 extend the illustrations beyond the parts involved in or affected by the improvements herein claimed.

In Figs. 1 and 2, A represents the shed; B, the finished cloth; C, the cloth beam or roll upon which the cloth is wound, and D D stationary parts of the frame. The lay-frame, arranged appropriately in front of the cloth-beam C, is composed of uprights E E, respectively mounted at the bottom upon pivots E' 45 and connected near their tops, but below the shed, by a cross-beam F, above which they carry the reed f, of usual construction and

arrangement, and which is seen in end elevation in Fig. 2 and is also indicated by the dotted line f in Fig. 1. The lay-frame is connected by a pitman e with a crank e' on a shaft e², which receives appropriate motion properly timed, as hereinafter indicated. This construction is common or is in no way essential to the present invention. On the front 60 of the lay-beam F is mounted a beam G, having formed in it a dovetailed track or way in which fits and slides a block or carriage H, having a laterally-projecting L-shaped bracket H', carrying a vertical post H², apertured near its top for the reception of the needle end, which is adjustably secured in the post by a set-screw h, the needle being thus held at an appropriate elevation to properly pass through the shed. The general 70 shape of the needle is seen particularly in Fig. 1, from which it appears that the needle is bent in its length so that its eye end lies parallel with and above the bar in which the needle-carrier travels, whereas its outer end is in a plane in front of such bar.

A shaft I, to be appropriately mounted in suitable bearings and whose axis is at right angles to the transverse plane of the machine, is located at the lower right-hand side of the 80 machine and has upon its inner end a disk I'. A pin I² on the disk works in a curved slot in a vibrating arm K, fast upon a rock-shaft K', turning in appropriate bearings at the bottom of the machine and whose axis is parallel 85 with that of the shaft I. The upper end of the arm K is transversely slotted, and in this slot, by means of a clamping-bolt, is adjustably secured a rearwardly-projecting horizontal finger or plate k', which lies closely between rollers l l, mounted on brackets secured to the rocking needle-actuating arm L, which is pivoted at its lower end upon the rock-shaft K' on an axis l' substantially parallel 90 with that of the lay-frame, and is therefore capable of following or conforming to its vibratory movement. The upper end of the rocking arm L passes loosely through the recess or opening of the L-shaped bracket H', projecting laterally from the block traveling 100 in the guide or way in the bar or beam G. As the lay-beam vibrates the rocking arm L, by reason of its engagement with the bracket H', follows its movement, while at the same

time the coöperating or actuating relation between the arm L and the slotted arm K, driven by the disk on the shaft I, is maintained by the horizontal plate or finger k'. The upper end of the rocking arm L is provided with a bearing-block l², in which is mounted a transverse pin l³ on the end of a cylinder or sleeve l⁴, Fig. 3, the opposite end of which is tapped to receive the threaded end of a bolt l⁵, the opposite end of which is formed with an eye or hub l⁶, fitting over a pin projecting from the needle carrier or block H, working in the way in the beam G. As, therefore, the rocking arm L is vibrated the needle-carrier is reciprocated. Appropriate adjustment of the connections is provided by the adjustment of the finger k' in the slot in the rocking driven arm K and by the adjustment of the connection between the upper end of the rocking arm L and the needle-carrier H, while, as before stated, the needle may be adjusted in its supporting post H². On the needle carrier or block H, inside of the connection l⁶, is an apertured post m, in which is adjustably mounted, by means of a set-screw, a rod m', projecting parallel, or substantially so, with the beam G and bent outwardly at its end, for a purpose hereinafter described.

While I may employ the usual weft-thread tension device mounted upon the frame of the loom, I prefer to provide in connection with it or in lieu of it a tension device on the reciprocating needle, and such device in the form in which I have constructed and practically used it is illustrated in Figs. 9 and 1. The outer straight portion of the needle is formed horizontally with an enlarged opening, at each side of which is a guide-tube n n', preferably arranged parallel with the axis of this part of the needle for the entrance and exit of the weft-thread x. Within this opening are two oppositely-arranged tension devices n², pivoted, preferably, at their ends adjacent to the guide-tube n, at which the weft-thread enters, and each having, as shown in the present instance, three laterally-projecting eyes, the eyes on one device being arranged opposite the spaces between the eyes on the other. The two opposite devices are normally drawn away from each other by springs or elastic bands n³, engaging them and attached to the body of the needle, and their other ends are guided in a slotted piece n⁴, bridging the opening in the needle. By grasping the two tension devices they may be pressed toward each other, so that the eyes of both are in line. The weft-thread x may be then pressed through the tube n, through the eyes of the tension device, thence through the eye n' to the eye in the point of the needle. When the tension devices are released, they move away from each other and the weft-thread is drawn into the M-shaped condition shown in Fig. 9. I prefer to employ elastic bands in lieu of metal springs, as in the event

of breakage the metal parts might fall from the needle and injure the fabric or yarns.

In Figs. 1 and 2 the reed is shown as just having beaten in a weft and it and the lay-frame are retreating. At the left-hand side of the machine a channeled shuttle-carrier O, Figs. 1 and 4, is pivotally connected at o with the lay-beam or the beam G. The shuttle S floats or lies in the channel and is formed with side ribs s, that extend under the overhanging sides o' of the carrier to prevent the shuttle from being jarred out of place. In the rear of the shuttle a plate P lies loosely in the channel of the reciprocating carrier O and at its outer end is pivotally connected at p with a fixed part of the frame D. The plate P, turning on its pivot p, may be lifted up, when desired, out of the channel, in which it normally lies, and the pivotal connections o p permit the reciprocation of the carrier O without disturbing the proper coöperating relation between the carrier and the non-reciprocating plate P. A spring P', applied to the plate P and attached to a stationary part of the frame, normally draws the plate against the bottom of the channel in the carrier O. A shuttle-guard S', shown in the form of a bent wire, is attached to the plate P at a suitable point in rear of the shuttle and extends forward over the shuttle, its end resting lightly upon or in close proximity to the shuttle near its point and preventing endwise movement of the shuttle as the carrier vibrates. Immediately in rear of the shuttle is a star-wheel Q for receiving the weft-loop from the shuttle and releasing it at the proper time. This wheel turns in or on a proper bearing at the end of the plate P and has a smaller star-wheel Q' attached to its upper face. An endwise-movable bar p² is mounted in posts p³ p⁸ on the plate P, and a spring p⁴, applied to it between the posts, normally draws it away from the shuttle. At one end it carries a spring latch or pawl p⁵, acting upon the star-wheel Q', and at the other has several lateral projections, teeth, or pins p⁶, between which normally lies one end of a lever R, pivoted on a fixed rod or bar R', projecting from the frame-bar D below the plate P. On this lever is a pivoted spring-controlled latch R², which is operated upon by an arm R³, adjustably mounted in a block R⁴, attached to the beam G. In the shuttle-carrier O is a transverse groove or trough o' to receive the needle in its advanced position, and appropriately related to this trough is the pivoted hook or looper T, that takes the loop of weft from the needle and delivers it to the shuttle. The arm of this hook is adjustably secured upon a rock-shaft T' of appropriate length turning in bearings T² on the top of the beam G and having at its inner end a projecting arm t to be struck at the proper time by the rod or arm m' on the needle-carrier H to actuate the hook in proper relation to the needle. At any suitable point in the length of the rock-shaft T' a wedge-shaped block t' is

attached to it, which co-operates with a correspondingly-shaped block t^2 , which is mounted to move endwise in a bracket t^3 on the beam G and is normally urged by a spring t^4 into engagement with the part t' . The purposes of these devices are to assist the movement of the shaft and hook T into either of two positions and to retain it therein until positively moved into the other position, as will be presently described.

The operation is as follows, the shafts e^2 and I being properly timed and actuated from any suitable power connections: When the needle carrying the weft-thread has traversed the shed, it enters the groove o' in the shuttle-carrier O , and at that time the position of the lay-frame is such that the needle occupies the relation to the shuttle exhibited in Fig. 6. The rod m' on the reciprocating needle-carriage has acted against the arm t on the hook rock-shaft and the wedge-shaped block or wiper t' on that shaft has been thrown down, snubbing back the wedge-shaped block t^2 until it passes beneath it, when the reaction of the spring t^4 further depresses the wiper t' and completes the movement of the hook, bringing it into the position shown in Fig. 6, where it passes between the upper face of the needle and the weft-thread. As the lay-frame continues to advance the needle recedes and the loop of the weft, Fig. 7, is passed over the nose of the shuttle, the lower part of the loop lying in the groove o' , insuring its passage under the shuttle, while the upper strand of the loop is directed above the shuttle by the supporting-hook. As the lay-frame continues to advance the loop is further carried over or around the shuttle until the projection V or the outer end of the hook-arm above the hook comes against a stop-arm V' , projecting from the frame, when the hook is thrown back, (the operation of the parts t^1 t^2 being now repeated, but in a reverse direction.) The hook is restored to its normal position, being withdrawn from the loop, which now slips entirely past the shuttle and engages a tooth of the star-wheel Q , Fig. 8. At this time the rod R^3 strikes the latch R^2 on the lever R , the upper end of which is forced against one of the pins p^2 , the pawl p^5 is moved forward to act upon the small star-wheel Q' , and a partial rotation is imparted to the wheel Q in the direction of the arrow, Fig. 8, so that the weft-loop is delivered from the tooth of the wheel and is drawn down upon the selvage or shuttle thread W by the continued retreat of the needle to its normal or initial position. The weft or filling is beaten home by the reed and the lay-frame then retreats.

For purposes of adjustment multiple pins or teeth p^6 are provided, the rod R^3 is adjustably mounted in its support, and the hook T is adjustably connected with its rock-shaft.

The construction illustrated and described has been demonstrated by practical use to be an efficient one and is the best now known to me. Obviously, however, those skilled in the

art may devise modifications or changes in the structure without departing from the spirit of the invention or materially changing the construction or mode of operation.

I claim as my invention—

1. The combination with a vibrating lay-frame, of a reciprocating needle-carrier carried thereby, a needle-carrier-actuating arm operatively connected with the needle-carrier and capable of rocking to reciprocate the needle-carrier transversely and also to follow the to-and-fro movement of the lay-frame, a rotating driving-disk, a rocking slotted arm vibrating in a plane parallel with the disk, a sliding or loose pin connection between the disk and slotted arm and an elongated sliding operative connection between the slotted arm and the needle-carrier-actuating arm. 85

2. The combination of the rotating disk or actuating device, an arm vibrated thereby, a rock-shaft upon which the arm is mounted, a vibrating needle-carrier-actuating arm rocking on an axis carried by the rock-shaft and at right angles thereto, a vibrating lay-frame, the reciprocating needle-carrier carried thereby, an extensible or sliding operative connection between the two rocking arms and an operative connection between the needle-carrier 95 and its actuating-arm.

3. The combination of the lay-frame and needle-carrier, of the needle-carrier-actuating arm having motion about an axis parallel with the axis of the lay-frame, and also about an axis at right angles thereto, a driven vibrating arm rocking about an axis at right angles to that of the lay-frame, a finger or blade projecting therefrom and rolls mounted on the needle-carrier-actuating arm and between which said blade works. 105

4. The combination of the vibrating lay-frame, a reciprocating needle-carrier mounted thereon, means for reciprocating it during the vibration of the lay-frame, the shuttle-carrier mounted upon and moving with the lay-frame and having a transverse passage therein for the reception of the needle in its advanced position, a hook moving with the lay-frame, means for actuating it when the needle is in its advanced position to engage the weft-thread loop before it is passed over the shuttle, the floating selvage-shuttle mounted in the shuttle-carrier, and means for retracting the hook or disengaging it from the weft-thread loop when the needle has receded from said groove and the weft-thread loop has been carried over or around the shuttle. 115 120

5. The combination of the vibrating lay-frame, a reciprocating needle-carrier mounted thereon, means for reciprocating it during the vibration of the lay-frame, the shuttle-carrier mounted upon and moving with the lay-frame and having a transverse passage 130 therein for the reception of the needle in its advanced position, a hook moving with the lay-frame, means for actuating it when the needle is in its advanced position to engage

the weft-thread loop before it is passed over the shuttle, the floating selvage - shuttle mounted in the shuttle-carrier, means for retracting the hook or disengaging it from the weft-thread loop when the needle has receded from said groove and the weft-thread loop has been carried over or around the shuttle, and means for preventing the shuttle from following the movement of the shuttle-carrier.

6. The combination of the vibrating lay-frame, a reciprocating needle-carrier mounted thereon, means for reciprocating it during the vibration of the lay-frame, the shuttle-carrier having a transverse groove therein for the reception of the needle in its advanced position, a hook, means for actuating it when the needle is in its advanced position to engage the weft-thread loop, the floating shuttle containing the selvage-thread, means for retracting the hook or disengaging it from the weft-thread loop when the needle has receded from said groove and the weft-thread loop has passed over or around the shuttle, a toothed or star wheel arranged in rear of the shuttle to receive the weft-loop upon a tooth thereof as it leaves the shuttle, and means for rotating the wheel to release the weft-loop so that it may be drawn upon the selvage-thread by the retreating needle.

7. The combination with the vibrating lay-frame, the reciprocating needle-carrier and needle, of the transversely-grooved shuttle-carrier, the shuttle therein, the intermittently-operated hook, the plate lying in or on the shuttle-carrier in rear of the shuttle, the toothed or star wheel carried thereby, means for intermittently operating it, a pivotal connection between said plate and the main frame and a pivotal connection between the lay-frame and the shuttle-carrier.

8. The combination of a vibrating lay-frame, a reciprocating needle carried thereby, the transversely-grooved shuttle-carrier connected to and vibrating with the lay-frame, an intermittently-actuated hook to engage the weft-thread loop while the needle is in its advanced position in said groove and to hold it as the needle retreats, and a floating selvage-thread shuttle, mounted in said carrier, over which the weft-loop is passed as the lay-frame advances, and means for preventing the shuttle from following the movement of the shuttle-carrier.

55. 9. The combination of the vibrating lay-frame, the reciprocating needle carried thereby, a transversely-grooved shuttle-carrier carried by the lay-frame, an intermittently-operated hook to engage the weft-thread while the needle is in its advanced position in said groove, a plate lying in or on the shuttle-carrier in the rear of the shuttle and pivotally connected to a fixed part of the frame, and means carried by said plate for preventing the endwise travel of the shuttle as the carrier vibrates with the lay-frame.

60. 10. The combination of the vibrating lay-

frame, the reciprocating needle carried thereby, a transversely-grooved shuttle-carrier carried by the lay-frame, an intermittently-operated hook to engage the weft-thread while the needle is in its advanced position in said groove, a plate lying in or on the shuttle-carrier in the rear of the shuttle and pivotally connected to a fixed part of the frame, means carried by said plate for preventing the endwise travel of the shuttle as the carrier vibrates with the lay-frame, and devices carried by said plate for preventing the endwise travel of the shuttle as the carrier vibrates with the lay-frame, and devices carried by said plate for delivering, at the proper time, the weft-loop after it has passed over the shuttle.

11. In a needle-loom the combination of the reciprocating needle, an intermittently-operated hook to take the weft-loop from the needle, the floating selvage-thread shuttle over which the loop is then passed, the star or toothed wheel arranged in rear of the shuttle and a tooth of which receives the weft-loop when it leaves the shuttle and means for intermittently operating the wheel to release the weft-loop.

12. The combination of the vibrating lay-frame, the reciprocating needle-carrier traveling in a way or guide on said frame, the hook, its rock-shaft turning in bearings on said frame, means for partially actuating the rock-shaft when the needle-carrier has reached its advanced position, devices for completing the actuation or movement of the rock-shaft and holding it in position, and means for subsequently restoring the hook to its normal or initial position.

13. The combination of a vibrating lay-frame, the reciprocating needle and needle-carrier carried thereby, a hook coöperating with the needle to take the weft-thread therefrom, a rock-shaft on which the hook is mounted having bearings on the lay-frame, a projection on the rock-shaft, a coöperating projection on the needle-carrier, a wedge-shaped wiper on the rock-shaft and a coöperating yielding wedge-shaped rod or block, and a stop on the frame against which the hook strikes and by which the hook is restored to its normal or initial position to release the weft-loop at the required time.

14. The combination of a vibrating lay-frame, a needle-carrier reciprocating in a guide or way thereon, a driven vibrating needle-carrier-actuating arm mounted to follow the vibration of the lay-frame, a loose connection between the needle-carrier and vibrating arm by which the arm is carried with the lay-frame in its vibrations and an independent actuating connection jointed at one end to said arm and at the other end to the needle-carrier whereby the needle-carrier is reciprocated as the arm vibrates about an axis transverse to that of the lay-frame.

15. The combination of the vibrating lay-frame, a needle-carrier reciprocating thereon, a needle-carrier-actuating arm mounted to follow the movement of the lay-frame and to vibrate to reciprocate the needle-carrier, and

- operative connection between said arm and the needle-carrier, a hook coöperating with the needle, its rock-shaft mounted on the lay-frame, the shuttle-carrier mounted on and moving with the lay-frame, the floating shuttle lying in the carrier, means for preventing the shuttle from following the movement of the carrier and means whereby the hook is intermittently actuated to coöperate with the needle and shuttle.
16. The combination of the vibrating lay-frame, a needle-carrier reciprocating thereon, a needle - carrier - actuating arm mounted to follow the movement of the lay-frame and to vibrate to reciprocate the needle-carrier, an operative connection between said arm and the needle-carrier, a hook coöperating with the needle, its rock-shaft mounted on the lay-frame, the shuttle-carrier mounted on and moving with the lay-frame, the floating shuttle lying in the carrier, means for preventing the shuttle from following the movement of the carrier, means whereby the hook is intermittently actuated to coöperate with the needle and shuttle, and means for delivering the weft-loop at the proper time, after it has been passed over the shuttle by the forward movement of the lay-frame.
17. In a needle-loom the combination of a weft-thread needle, means for reciprocating it transversely and moving it laterally to and fro within the shed, a shuttle-carrier following the to-and-fro movement of the needle, a hook traveling with the shuttle-carrier, means for operating the hook to take the weft-loop from the needle when the needle has been reciprocated through the shed into its advanced position and hold it as the needle retreats, a floating shuttle mounted in the carrier and held in a normal fixed position over and around which the weft-loop is passed as the hook advances, and means for disengaging the hook from the loop after the loop has passed over the shuttle.
18. In a needle-loom the combination of a weft-thread needle, means for reciprocating it endwise transversely to the warps and moving it laterally to and fro within the shed longitudinally of the warps, a shuttle-carrier following the lateral to-and-fro movement of the needle, a hook traveling with the shuttle-carrier, means for operating the hook to take the weft-loop from the needle when the needle has been reciprocated through the shed into its advanced position and hold it as the needle retreats, a floating shuttle mounted in the carrier and held in a normal fixed position over and around which the weft-loop is passed as the hook advances, means for disengaging the hook from the loop after the

loop has passed over the shuttle, and means for releasing or delivering the loop at the proper time as the needle retreats.

19. In a needle-loom the combination of a weft-thread needle, means for reciprocating it endwise transversely to the warps and moving it laterally to and fro within the shed longitudinally of the warps, a hook following the lateral to-and-fro movement of the needle, means for operating the hook to take the weft-loop therefrom when the needle has been reciprocated through the shed into its advanced position and hold it as the needle retreats, a floating shuttle held in a normal fixed position over and around which the weft-loop is passed as the hook advances, and means for disengaging the hook from the loop after the loop has passed over the shuttle.

20. In a needle-loom the combination of a weft-thread needle, means for reciprocating it endwise transversely to the warps and moving it laterally to and fro within the shed longitudinally of the warps, a hook following the lateral to-and-fro movement of the needle, means for operating the hook to take the weft-loop therefrom when the needle has been reciprocated through the shed into its advanced position and hold it as the needle retreats, a floating shuttle held in a normal fixed position over and around which the weft-loop is passed as the hook advances, means for disengaging the hook from the loop after the loop has passed over the shuttle, the loop-receiving device which receives and holds the loop after it has passed around the shuttle, and means for operating said device to discharge the loop at the proper time as the needle retreats.

21. In a needle-loom, the combination of the reciprocating needle formed between its ends with an enlarged loop or opening, and a tension device mounted in the opening.

22. In a needle-loom, the combination of the reciprocating needle formed between its ends with an enlarged loop or opening having apertures through its opposite walls for the passage of the weft-thread, and a tension device mounted in the opening and consisting of the opposed resilient members having eyes for the passage of the thread and a slotted piece bridging the opening and in the slot of which the free ends of said members are guided, substantially as set forth.

In testimony whereof I have hereunto subscribed my name.

JACQUES HOHL.
